UNITED STATES PATENT OFFICE

JOSEPH S. MOHR AND WILLIAM G. BORN, OF CHICAGO, ILLINOIS, ASSIGNEES TO JOHN MOHR & SONS, OF CHICAGO, ILLINOIS, A CORPORATION OF ILLINOIS

HOT METAL MIXER

Application filed July 8, 1931. Serial No. 549,378.

Our invention pertains to those appliances, or so-called hot metal mixers, which comprise receptacles for the molten metal and which may be swung or rocked to deliver the metal therefrom through a pouring spout, forming part of the metal container, and provided for that purpose.

One object of the invention is the provision of an apparatus of this character with distinct safety features, such as means to prevent the occurrence or possibility of a fire hazard by reason of sparks igniting an oil-bath and to preclude the splashing of hot metal due to breakage of parts.

By enclosing the various operating members as much as possible, they may be kept well lubricated with resulting small wear, and they are thus maintained comparatively free from dirt with its accompanying injurious effects.

A further aim of the invention is to supply a device of this character which is efficient and reliable in operation, which is unlikely to become damaged or injured in ordinary service, which can be economically maintained in proper operative condition, and in which there is adequate accessibility to the various parts.

To the accomplishment of these and other desirable purposes, the present, preferred embodiment of the invention has been developed and put into service, such apparatus being illustrated in the accompanying drawings, forming a part of this specification, and to which reference should be had in connection with the following detailed description, like reference numerals having been employed throughout the several views to designate the same parts.

In the drawings:—

Figure 1 is a side elevation of the entire apparatus, certain parts being broken away or shown in section to illustrate the construction more clearly;

Figure 2 is a plan view of the drive mechanism for the oscillatory, hot metal receptacle, with some of the cradles and their supporting rollers omitted to show the structure more fully;

Figure 3 is an end view of the appliance with parts broken away; and

Figure 4 is a fragmentary view presenting a modified means for operating the cover or closure for the inlet.

Referring to these drawings, it will be perceived that on a suitable foundation 11, such as reenforced concrete or the like, two aligned electric-motors 12 and 13, through flexible couplings 14 and 15, operate a fully-enclosed, worm-gear, speed-reduction mechanism 16 between them and connected by a shaft 17 and associated coupling 18 to a similarly adequately-enclosed, double-reduction, herringbone-gear unit 19, which, through a coupling 21, rotates a main-shaft 22 divided into sections connected together by appropriate couplings 23 and 24.

Motor 13 and its shaft, by means of suitable gearing 25, is operatively united with a non-reversing air-engine 26 of known type which comes into operation as a safety means, in case, by accident, the electric current supply should be temporarily cut off from the motors.

Shaft 22 revolves in a number of bearings 27, 28, 29, 30, 31 and 32, and it is equipped with three pinions 33, 34 and 35 for rocking the mixer by means hereinafter set forth.

At the sides of such shaft, a plurality of pillar-blocks or bearing-members 36 are so located in two, aligned groups or series, and each of such members is equipped with a rocker-shaft or roller 37 on which a cradle 38 is rockingly supported, each such cradle carrying a pair of antifriction, flanged rollers 39, 39 which support the mixer, characterized as a whole 41.

The mixer, the lower portion of which is of cylindrical shape, comprises a metal shell 42 suitably lined with refractory material 43, such shell being embraced within reenforcing circular bands 44, 44 in register with, and supported on, the corresponding cradle rollers 39, 39, the upper ends of such bands 44 being tied or connected together above the flattened top or arch of the mixer by tie-bars 45, 45.

Fastened to the sides of three of such encasing and encircling bands 44 are the corresponding number of gear-segments 46 in

mesh with, and adapted to be operated by, the correlated pinions 33, 34 and 35, whereby the mixer may be swung or rocked to pour out or deliver its molten contents and then rocked back to normal position.

On its relatively-flat top, the mixer has two inlet or admission openings 47, each fitted with a refractory-lined cover or closure 48 rockingly mounted at 49 on an arm 51 hinged at 52 and adapted to be actuated by a link 53 connected at 54 to the arm, and joined, at its other extremity, at 55 to an arm 56 fixed on the end of a shaft 57 mounted in bearings 58, 58 and revolved by an electric-motor 59, working through a double-reduction, worm-gear speed-reducer 61.

From the illustration, it will be clear that each cover 48 has its own independent operating mechanism of the nature described.

Midway between the pair of inlet openings 47, 47, at one side, the mixer has a pouring spout 62 of the usual construction, through which the molten contents of the receptacle are adapted to be discharged upon rocking the container to accomplish the specified result.

As is clearly illustrated, the cross tie-bars 45 act as supports for other bars, the whole constituting a fitting framework for carrying the cover-operating mechanisms described and other parts of the structure.

In order to strengthen and stiffen the construction and to assist in supporting the arched top 63 of the container, appropriately-shaped plates 64 are employed between the channel tie-bars 45 and the metal shell 65 of the mixer top 63, such plates being secured to the specified metal casing 65, to the cross-bars 45, and to the upper end parts of the bands or strips 44 by angle-bars 66, 67 and 68, respectively, on opposite sides of the plates, the whole, in effect, constituting stiffening and supporting webs.

In Figure 4 a somewhat different and preferred form of cover-operating mechanism has been illustrated.

In this case, a bent, supporting arm or arms 71 is or are hinged at 72 on a bracket or brackets 73 on the top of the mixer, and the inlet opening cover 74 is joined to the part 71 by a pin and slot connection 75, a link 76 hinged to the cover at 77, also having a pin and slot connection 78 with the part or parts 71.

As in the previous case, the electric, motor-driven shaft 79 has an arm 81 fastened to its end, and such arm, by a link 82, is connected to the member or members 71.

Revolution of shaft 79 will raise and lower the cover through the specified connections, and owing to the loose joining of the cover to the part or parts 71, it may effectually close the opening with which it is associated owing to its capacity for limited play with the parts on which it is mounted.

From the foregoing, it will be apparent that either cover or closure may be raised by the actuating means set forth and the hot metal introduced into the container, and, when it is desired to discharge a portion or all of the contents of the mixer, the latter is rocked by the intermeshing gear and pinion mechanism, the pinions being rotated by the main shaft on which they are mounted, the shaft, of course, being revolved by the pair of motors through the speed-reducing mechanism.

The construction is such that one or more of the speed-lessening means is non-reversible, such as by the use of a worm and worm-wheel, so that the mixer is always under control, the appliance being fitted desirably with automatically-acting limit switches 83, 83 to terminate the operation of the motors at the proper time.

In case, the electric current should fail or be cut off at an inopportune moment, as, for example, when the mixer is pouring out the hot molten metal, it can still be readily returned to its normal, non-pouring position by resorting to the non-reversing air-engine 26, which then temporarily acts as the power substitute for the motors.

It will be observed that the various parts of the operating mechanism are encased or enclosed in substantial measure, thus assuring adequate lubrication, the exclusion of dirt, and the elimination of possibility of any of the lubricant baths in which the moving parts operate becoming ignited by sparks.

Furthermore, all of the elements of the mechanism are comparatively readily accessible for replacements when such are required due to their wearing out in service.

The invention is defined in the appended claims, but it is to be borne in mind that it is susceptible of a variety of embodiments and is not necessarily limited to the precise and exact structural details herein described and illustrated in the drawings.

In other words, substantial changes may be made in the illustrated construction without departure from the principles of the invention and without the loss or sacrifice of any of its material benefits or advantages.

In some cases, it may be desirable to equip the spout mouth with a cover or closure, and in Figure 3 such a construction has been shown, comprising a suitable-shaped cover 102 hung on chains 101, 101 attached to a fixed or stationary support 100, so that when the mixer is in its non-pouring position shown, its spout is closed by the cover, but, when the mixer turns, its spout rocks away from the relatively, but not exactly, stationary cover, which has a certain amount of play by reason of slight slack in the carrying chains when the cover rests on the spout.

By providing the mixer with an inlet or admission opening on each side of its de-

livery-spout, either opening may be used for the introduction of the hot metal, and, by careful choosing of the openings for use, a more uniform mixture may be had when the melts vary materially in quality.

5 Whereas, the mixer operating mechanism has been characterized as non-reversible, by this is meant that the mixer cannot operate the driving means, although the latter, of course, is capable of rocking the mixer in opposite directions.

We claim:

1. In a hot metal mixer, the combination of a container adapted to receive the molten metal and having a pouring-spout through which it may be discharged, said container comprising a metal-shell lined with refractory material, the lower portion of said container being of cylindrical shape, its top being relatively flat, bands encircling said cylindrical part and extending up beyond said top, tie-bars cross connecting together the upwardly-extended ends of said bands over said top, web-plates between said tie-bars and the 25 container top, means securing said web-plates to said top, tie-bars, and upper portions of said bands, and means to rock said container on said bands.

2. In a hot metal mixer, the combination of a container adapted to receive the molten metal and provided with a pouring-spout through which it may be discharged, means 30 rockingly supporting said container, means to rock said container to initiate and to terminate the pouring operation, and a substantially stationary closure for said spout and away from which the spout rocks when turned to start the pouring operation.

In witness whereof we have hereunto set 35 our hands.

WILLIAM G. BORN.
JOSEPH S. MOHR.
